UNITED STATES PATENT OFFICE.

CARLETON ELLIS, OF NEW YORK, N. Y., ASSIGNOR TO ELDRED PROCESS COMPANY, OF NEW YORK, N. Y., A CORPORATION OF NEW YORK.

WATER-SEAL GAS-PRODUCER.

SPECIFICATION forming part of Letters Patent No. 793,362, dated June 27, 1905.

Application filed March 15, 1905. Serial No. 250,179.

To all whom it may concern:

Be it known that I, CARLETON ELLIS, a citizen of the United States, and a resident of New York city, in the county of New York and State of New York, have invented certain new and useful Improvements in Water-Seal Gas-Producers, of which the following is a specification.

My invention relates to improvements in gas-producers of the water-seal type; and the object of my improvement is to provide a method for the introduction of the air-blast which will allow of the production of a combustible gas of uniform composition and of high quality and which will also distribute the air in such a way that the present large losses in fuel through the presence of unburned carbon in the ash will be avoided. I attain these objects by the apparatus illustrated in the accompanying drawings, in which—

Figure 1 is a vertical section of the entire apparatus; Fig. 2, an elevation of the apparatus, showing also details of the blast-pipe and connections with suitable blast-producing appliances.

Similar numbers refer to similar parts in the two views.

In Fig. 1 the shell 1 is lined with fire-brick or other refractory material 2. 3 is an outlet for the combustible gas; 4, a hopper for the introduction of fuel, having the lid 5 and coal-spreading device 6. The lower portion of the producer is constricted, forming the shoulder 7. 8 is a water seal in which the lower part of the producer rests on the supports 9. 10 is a blast-baffle having inclined sides 11, terminating in the lower part of the slope in an upward-deflecting ridge, thereby forming a sort of gutter. In the center of this blast-baffle is situated a blast-pipe 12, terminating in the nozzle or twyers 13. Fig. 2 shows more clearly the construction of these twyers. Poking-holes in the walls of the producer are shown at 14. The blast-pipe 12 connects with the inlet-pipe 15, in which are shown two appliances for producing a blast. One of these, 16, is a steam-blower having the steam-jet 17 and blast-gate 18. The other appliance, 19,

is a fan-blower having inlet-pipes 20 and 21 for the introduction of products of combustion and air, respectively. Adjusting-gates are shown at 22 and 23.

My method of operation is as follows: A fire is started in the producer and coal is fed in through the hopper until a deep bed of ignited coal is obtained. When in a state of ignition suitable for the production of gas, an air-blast is directed through the twyer-pipe 12 and discharges from the twyers 13 onto the inclined blast-baffle 10. The blast is thus deflected outwardly toward the walls of the producer, but is prevented from forcibly striking the walls thereof by the baffling action of the gutters on the lower part of the slopes. The blast, therefore, after moving downward for a short distance reverses in direction and moves upwardly, being thereby dispersed in such a manner that its uniform passage through the bed of fuel is insured. The constricted walls of the lower part of the producer tend to prevent the blast from seeking the walls. The initial downward movement of the air-blast tends to burn out of the ash all unconsumed carbon. The blast may be created by admission of steam through pipe 17 or by operating the fan 19. The products of combustion used in the latter case may be drawn from any suitable furnace or kiln. Lime and cement kilns furnish a gas particularly adapted for use for this purpose, owing to their richness in carbon dioxid and to their consequent low content of inert nitrogen.

What I claim is—

1. A gas-producer comprising a shell lined with refractory material having in its upper part hoppers for the introduction of fuel, an outlet for the delivery of the combustible gas, a water seal, a blast-baffle diametrically located within the shell having pitched or inclined sides, and a blast-pipe terminating in twyers for the distribution of the air-blast downwardly against the inclined sides of said baffle.

2. A gas-producer comprising a shell adapted to contain a deep bed of fuel, near its top a gas-outlet and means for introduction of fuel, at its bottom a water seal and a therein

centrally-rising blast-baffle having sloping sides, in the center of said baffle a blast-pipe so arranged as to deliver an air-blast downwardly upon the sloping sides, connections with said blast-pipe for the introduction of a cooling medium in conjunction with said air-blast.

Signed at New York city, in the county of New York and State of New York, this 13th day of March, A. D. 1905.

CARLETON ELLIS.
